No. 776,257.

PATENTED NOV. 29, 1904.

O. S. PULLIAM.

DRAFT RIGGING CARRIER FOR CAR SILLS.

APPLICATION FILED APR. 18, 1904.

NO MODEL.

Attest:

Mr. Smith
Blanche Hogan

Inventor;
O. S. Pulliam
By Knight, Port attys.

UNITED STATES PATENT OFFICE.

OSWALD S. PULLIAM, OF ST. LOUIS, MISSOURI, ASSIGNOR TO COMMONWEALTH STEEL COMPANY, OF ST. LOUIS, MISSOURI, A CORPORATION.

DRAFT-RIGGING CARRIER FOR CAR-SILLS.

SPECIFICATION forming part of Letters Patent No. 776,257, dated November 29, 1904.

Application filed April 18, 1904. Serial No. 203,669. (No model.)

To all whom it may concern:

Be it known that I, OSWALD S. PULLIAM, a citizen of the United States, residing in the city of St. Louis, in the State of Missouri, have invented certain new and useful Improvements in Draft-Rigging Carriers for Car-Sills, of which the following is a full, clear, and exact description, reference being had to the accompanying drawings, forming part of this specification.

My invention relates to a construction of draft-rigging carriers designed for use in connection with a cast-metal car-sill, the object of the invention being to secure an arrangement whereby the sill and rigging-carrier are rendered a unit.

Figure I is a top or plan view of a pair of my draft-rigging carriers shown applied to a cast car-sill and car-body bolster associated therewith. Fig. II is an enlarged perspective view of one of the draft-rigging carriers. Fig. III is a longitudinal vertical section taken on line III III, Fig. I. Fig. IV is an enlarged vertical cross-section taken on line 25 IV IV, Fig. I. Fig. V is a perspective view of a modification of my draft-rigging carrier. Fig. VI is a section similar to Fig. IV, illustrating a modification of my improvement.

1 designates a cast-metal car-sill. This sill 30 is provided with reduced ends 2, as seen in Fig. I.

3 designates the draft-rigging carriers, which are bifurcated at their rear ends to form fork-arms 4, that straddle the reduced 35 ends of the car-sill and are secured thereto by any suitable means, such as bolts 5. The sides 6 of the carriers 3 are connected by transverse ties 7, and in the forward ends of said sides are longitudinal slots 8. The forward ends of the sides being separated, provision is thereby made for the positioning of the draw-bar of the draft-rigging (indicated by dotted lines at A, Fig. 1) between said sides, and the slots 8 serve as guideways for 40 the guides B of said draw-bar. At the top edges of the draft-rigging-carrier sides are notches 9, and at the lower edges of said sides are notches 10. These notches are made in

the carriers to provide seats for a separable body-bolster and its removable center plate, 50 which bolster may be the construction illustrated in Letters Patent of the United States No. 753,112, issued February 23, 1904, to the Separable Body Bolster Company. The upper central parts of the bolster (designated 55 by 11) fit into the notches 9 of the carriers. The central portion 12 of the bolster occupies a position intermediate of the carrier sides 6, and the removable bolster center bearing 13 is fitted to the lower edges of the carrier sides 60 and the lower end of the bolster central portion 12. It will be seen that by this construction I am enabled to provide a car-sill with draft-rigging carriers extending directly from the ends of the sill, whereby the sill 65 and rigging-carriers constitute a single unit, and that I also provide for the mounting of the car-body bolsters in connection with the rigging-carriers in a manner whereby they are gradually included in the unit embodying the 70 car-sill and draft-rigging carriers.

In Fig. V, I have shown a modification in which the construction of the draft-rigging carrier is in the main the same as that previously described, but in which the forward ends 75 of the carrier sides are united by top portions 14, thereby rendering the forward ends of the carrier of box instead of skeleton form, as in the construction previously described. The remaining features in this construction corresponding to the previously-described construction are designated by the same numerals as those previously used with the affix-letter "a" applied thereto.

In Fig. VI, I have illustrated another modification wherein the center plate 13', that fits to the bolster 11', is made integral with the carrier 3 instead of being a part separate therefrom and is provided with upwardly-projecting ribs 13", that take the place of the 90 sides of the draft-rigging carrier at the location of the notches therein, as previously described, and which fit against the central portion 12' of the bolster. In this construction the bolster is fitted to the center bearing of 95 the draft-rigging carrier by applying it from

above and is secured to said center bearing by any suitable means, such as the bolts 15.

I claim as my invention—

1. The combination with a cast-metal car-sill, of draft-rigging carriers secured to the ends of said sill and arranged to receive and hold body-bolsters applied thereto, substantially as set forth.

2. The combination with a cast-metal car-sill, of draft-rigging carriers secured to the ends of said sill, said carriers being notched to receive body-bolsters applied thereto, substantially as set forth.

3. The combination with a car-sill, of draft-rigging carriers connected to the ends of said

sill and having their sides notched at their upper and lower edges, body-bolsters fitted to said carriers and seated in said upper notches, and a center bearing seated in said lower notches, substantially as set forth.

4. The combination with a car-sill, of draft-rigging carriers secured to the ends of said sill, said carriers having slotted sides to receive a draw-bar, and notches intermediate of their ends to receive a body-bolster, substantially as set forth.

OSWALD S. PULLIAM.

In presence of—

E. S. KNIGHT,

NELLIE V. ALEXANDER.
